HIS ATTORNEY.

UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

RECIPROCATORY HAMMER TOOL.

Application filed October 29, 1924. Serial No. 746,464.

This invention relates to fluid actuated hammer tools, and more particularly to a valve motion for controlling the movements of the piston within the cylinder.

5 In hand held fluid actuated percussive tools of the free exhaust type, that is, those which are provided with a central exhaust controlled by the hammer piston, compression is desirable on the back stroke of the 10 piston since the force of the returning piston is gradually absorbed so that the operator receives less shock. On the forward stroke, however, it is desirable to relieve the compression so that the hammer may deliver its 15 full force to the bit. It is not difficult to provide an arrangement for relieving the compression at both ends of the cylinder as this has heretofore been the practice. This invention, however, provides a means for 20 relieving the compression at the front end of the cylinder so as not to retard the hammer piston while full compression is maintained on the rearward stroke to relieve the operator of the shock and to make an easy 25 holding tool.

One object of this invention is to provide for the escape of compression on the forward end of the cylinder through the interior of the valve.

30 Other objects of the invention will be in part obvious and in part pointed out in the following description taken in conjunction with the accompanying drawings, in which

Figure 1 is a longitudinal sectional view 35 of a hammer tool constructed in accordance with the practice of the invention and shows the valve in its operating position at the beginning of the forward stroke of the hammer piston.

Figure 2 is a longitudinal section of the hammer tool showing the piston beginning its return stroke, the valve being in its corresponding position.

Referring to the drawings, the hammer 40 tool comprises a cylinder A having a pair of piston controlled free exhaust ports B and C leading to atmosphere through the opening D in the cylinder wall. A tool E, such as a chisel or other suitable bit, is adapted to be inserted so as to project into the front end of the cylinder A in the path of the reciprocating piston F. The movements of the piston F are controlled by a cylindrical valve G which is adapted to re-

ciprocate in a valve chamber H set in the back of the cylinder A.

The valve chamber H is closed at its rear end by the back head J which is attached to the cylinder A by suitable bolts K. The handle part of which is shown at L is also held onto the back head J by the bolts K and a cross piece O.

The valve chamber H is provided with a pair of supply ports P and Q extending from a supply passage R which is associated with a suitable source (not shown) of compressed air. The ports P and Q lead to the front and rear ends of the valve chamber H in front and behind the valve G. The compressed air or other suitable motive fluid, is admitted into the cylinder A from the valve chamber H through inlet ports S and T which lead to the rear and front ends of the cylinder A respectively. The port T extends through the back head J to a longitudinal passage U in the cylinder wall to the front end of the cylinder. The valve chamber H is also provided with a port V leading to atmosphere through the cylinder wall and is arranged to cooperate with a passage leading from the port T associated with the front end of the cylinder A. This passage is provided in the valve G and includes a longitudinal bore W drilled part way into the valve and connected by a radial hole X with an annular groove Y in the periphery of the valve G intermediate its ends. As the valve G reciprocates, the annular groove Y is arranged to traverse the port V, the two cooperating so that on the forward stroke of the piston F the exhausted motive fluid in the forward end of the cylinder may pass back through the passage U and the port T into the interior of the valve W and thence through the hole X and the annular groove Y and the port V to atmosphere.

In order to throw the valve G, there are provided end pressure areas b and c which are constantly exposed to live air pressure 100 from the supply ports P and Q respectively. The pressure areas b and c oppose each other and cause the valve to move in one direction or the other when the piston F passes one of the exhaust ports B or C to lower the pressure of the motive fluid on one of these faces. For instance, when the valve G is in the position shown in Figure

1 and the piston F has advanced far enough to uncover the exhaust port C, the pressure on the area *b* drops because of the exhaust of air behind the piston through the exhaust port. Under these conditions the full line pressure on the area *c* is sufficient to cause the valve G to move forward whereupon a reversal in the supply of air to the inlet ports S and T takes place and the piston F 0 reverses its movement.

The operation of the hammer tool is as follows: assuming that the piston F and the valve G are in the position shown in Figure 1, motive fluid is supplied from the supply port P through the inlet port S into the cylinder A behind the piston F forcing it forward to strike against the tool E. As the piston F advances the air compressed in front of the piston escapes through the exhaust port B until the latter is covered by the piston whereupon the air is compressed through the passage U and the port T and is exhausted to atmosphere through the bore W, the radial holes X and the ring port Y 20 of the valve G and the port V to atmosphere. There can therefore be substantially no compression in the forward end of the cylinder A to retard the movement of the piston F in its movement toward the tool E. When the rear edge of the piston F uncovers the exhaust port C, the pressure on the forward face of the valve G is immediately reduced so as to be less in amount than the pressure on the opposite end area 25 *c* whereupon the valve G acting under the unbalanced pressure moves forward to the position shown in Figure 2. This motion causes the port V to be blanked by the outer surface of the valve G and simultaneously closes the ports S, at the same time opening the inlet port T leading to the forward end of the cylinder A and motive fluid passes thereto from the supply port T. The piston F then is returned by the live motive fluid 40 advancing against the compression on its backward face. The exhaust port C is first closed which traps the air in the rearward end of the cylinder A and as the piston F moves backwardly in the cylinder, this air is compressed absorbing the energy of the returning piston and relieving the shock. As the piston F uncovers the exhaust port B, the pressure at the inlet port T drops, causing a corresponding decrease in pressure on the 45 rear face of the valve whereupon the combined compression in the rearward end of the cylinder A and the live air pressure against the end area *b* causes the valve G to move in the direction the piston F is 50 moving to open the inlet port S. The piston F is then forced forward under the pressure of live air that is supplied from the supply port P as before described.

The construction of the valve G, as above described, provides a very simply manufactured arrangement which is very reliable in operation. It will also be noted that the position of the valve chamber set into the rear end of the cylinder A provides an arrangement which can be easily assembled 65 and removed for repair. 70

I claim:

1. A fluid actuated hammer tool comprising a cylinder having a piston controlled exhaust port, a hammer piston within the cylinder, a valve chamber, inlet ports establishing communication between the front and rear ends of said cylinder and the opposite ends of said valve chamber, supply passages leading to the said opposite ends of said valve chamber from a source of pressure fluid, a port venting to atmosphere from said valve chamber and located centrally thereof, a cylindrical valve located and adapted to reciprocate within said valve chamber, said valve being provided with end pressure areas constantly in communication with the supply passage to actuate the valve, and a passage in said valve body constantly in communication with the inlet port to 90 the front end of the cylinder and leading into a peripheral groove encircling the said valve body which is adapted to communicate with the said atmospheric vent in the valve chamber while the piston is traveling forwardly. 95

2. A fluid actuated hammer tool comprising a cylinder having a piston controlled exhaust port, a hammer piston within the cylinder, a valve chamber set in the rear end of said cylinder, supply passages leading from a source of pressure fluid to opposite ends of said valve chamber, inlet ports leading from the said valve chamber to the front and rear ends of the said cylinder, an atmospheric vent midway between the ends of the valve chamber, a pressure fluid throw valve in the valve chamber for regulating the admission of motive fluid to the cylinder, and adapted to reciprocate in 100 said valve chamber, a peripheral groove around said valve and a port in said valve constantly in communication with said groove and the admission port to the front end of said cylinder, the arrangement of 105 said groove, atmospheric vent in the valve chamber and port being such that while the valve admits pressure fluid to the back end of the cylinder the peripheral groove and the atmospheric vent in the valve chamber 110 are in communication, thereby venting the front end of the cylinder to atmosphere. 115

In testimony whereof I have signed this specification.

FRANCIS A. JIMERSON.
